FOREIGN PATENT DOCUMENTS

CN 2728368 Y 9/2005

Primary Examiner — Ian Simmons*Assistant Examiner* — Janice Lim(74) *Attorney, Agent, or Firm* — Hanrahan Law Firm, P.A.; Benjamin M. Hanrahan(57) **CLAIM**

The ornamental design for a bottle, as shown and described.

DESCRIPTION

FIG. 1 is a right side perspective view of a bottle, showing my new design.

FIG. 2 is a right side view thereof.

FIG. 3 is a rear view thereof.

FIG. 4 is a left side view thereof.

FIG. 5 is a front view thereof.

FIG. 6 is a top view thereof; and,

FIG. 7 is a bottom view thereof.

The broken line in FIG. 7 illustrates a portion of the article that form no part of the claimed invention.

1 Claim, 7 Drawing Sheets---
